UNITED STATES PATENT OFFICE.

THURE E. DAHL, OF NEW YORK, N. Y.

DESIGN FOR A BODY PART FOR ELECTRIC FIXTURES.

• 60,899.

Specification for Design.

Patented Apr. 25, 1922.

Application filed May 31, 1921. Serial No. 473,924. Term of patent 3½ years.

To all whom it may concern:

Be it known that I, THURE E. DAHL, a subject of the King of Sweden, residing at New York, in the county of New York and State of New York, in the United States of America, have invented a new, original, and ornamental Design for a Body Part for Electric Fixtures, of which the following is a specification, reference being had to

the accompanying drawing, forming part thereof.

The figure is a perspective view of a body part for electric fixtures, showing my new design.

I claim:

The ornamental design for a body part for electric fixtures, as shown.

THURE E. DAHL.
